[57] CLAIM

The ornamental design for a wrist watch, substantially as shown and described.

DESCRIPTION

FIG. 1 is a top eye perspective view of a wrist watch showing my new design;

FIG. 2 is a left side elevational view thereof, the right side being a mirror image thereto;

FIG. 3 is a top plan view thereof, the bottom being conventionally plain and unornamented;

FIG. 4 is a left end elevational view thereof; and

FIG. 5 is a right end elevational view thereof.
